(57) **CLAIM**

The ornamental design for a birthday tablecloth with photo sleeves, as shown and described.

DESCRIPTION

FIG. 1 is a front perspective view of a birthday tablecloth with photo sleeves showing the ornamental design of the tablecloth.

FIG. 2 is a right side perspective view thereof.

FIG. 3 is a rear perspective view thereof.

FIG. 4 is a left side perspective view thereof.

FIG. 5 is a top plan view thereof with the photo sleeves attached; and,

FIG. 6 is a top plan view thereof with the photo sleeves removed and depicting the adhering strips of the tablecloth.

The broken line showing of the table is included for the purpose of illustrating use and environment and forms no part of the claimed design.
